ATTORNEY

UNITED STATES PATENT OFFICE.

ALFRED G. WORMSER, OF HARRISBURG, PENNSYLVANIA.

SAFETY-RAZOR.

1,074,149.

Specification of Letters Patent. Patented Sept. 30, 1913.

Application filed March 31, 1913. Serial No. 757,890.

To all whom it may concern:

Be it known that I, ALFRED G. WORMSER, a citizen of the United States, residing at Harrisburg, in the county of Dauphin and 5 State of Pennsylvania, have invented new and useful Improvements in Safety-Razors, of which the following is a specification.

This invention relates to improvements in safety-razors, and more particularly to re-10 movable blade safety razors.

It is the object of this invention to provide a removable blade safety razor of simple hinged blade holder construction, which will readily allow the insertion or removal 15 of the blade by pushing upward upon the under side of one end of the clamping plate and the clamping plate is readily released to swing backward upon the blade seat producing a sanitary construction in which all 20 parts are readily exposed for cleaning.

While the preferred forms of this invention are illustrated upon the accompanying sheet of drawing, yet it is to be understood that minor detail changes may be made 25 without departing from the scope thereof.

Figure 1 is a perspective view illustrating the razor constructed in accordance with this invention with the blade in position and ready for use. Fig. 2 is a perspective view 30 illustrating the clamping plate released and swung back upon the blade seat for cleaning. Fig. 3 is a bottom plan view with the handle in section. Fig. 4 is a perspective view illustrating the partial opening of the holder for 35 the insertion or removal of a blade.

In accordance with this invention the blade 1 is removably retained in a two-part blade holder comprising a flat blade seat and guard 2 and a flat clamping plate 3 40 hinged to the back thereof by a pintle 4. A handle 5 is secured to the under side of the blade seat. The ends 6 of the clamping plate extend downward over each end of the blade seat and are provided with inturned 45 ears 7 some distance below the under surface of the seat. The downward extending ends of the clamping plate act as guides and position-members holding the blade firmly against transverse movement. The ends of 50 the seat are provided with cut out portions 8 to allow the passage of the ears 7 therethrough. A spring 9 is passed along the under side of the tenons 10 of the hinge and coiled about the pintle 4 between the outer

tenons of the blade seat and clamping plate 55 respectively and the extended ends are then brought forward so that each one will rest on and exert a downward pressure upon the respective ears 7 of the clamping plate.

As seen in Fig. 4 by grasping the handle 60 the thumb may exert an upward pressure upon one of the inturned ears and thereby raise the front of the clamping plate sufficiently to either insert or remove a blade. The extended ends of the spring 9 resting on 65 the upper sides of the ears, as seen in Fig. 3, when pressed upward against the under side of the guard cross the cut out portions 8 thereof and act as a stop for further opening of the holder. To swing the clamping plate 70 back for cleaning the ends of the spring 9 are brought together until the ears 7 are released and the ears may then pass through the cut outs 8 in the blade seat.

What I claim is:

1. In a safety razor, a two-part hinged blade holder comprising a blade seat, a clamping plate rotatably mounted thereon, spring engaging means upon each end of the clamping plate near the front edge extending a short distance below the seat, and a spring coiled about the hinge pintle provided with extensions adapted to engage said means for normally drawing the plate and seat together and allowing a limited rotation of the plate to insert or remove a blade. 75

2. In a safety razor, a two-part hinged blade holder comprising a flat blade seat, a flat clamping plate rotatably secured to the back of the seat, blade guides and positioning members thereon provided with inturned ears arranged at a distance below the seat, the seat having cut out portions allowing the ears to pass therethrough, and a spring 90 coiled about the hinge pintle for drawing the plate and seat together having extending ends normally engaging the inturned ears upon the under side of the seat allowing a limited upward rotation of the clamping plate to insert or remove a blade. 95

3. In a safety razor, a two-part hinged blade holder comprising a flat blade seat, a handle secured to the under side thereof, a flat clamping plate rotatably secured to the 100 back of the seat having overlapping depending ends with inturned ears, the seat having cut out portions allowing the ears to pass

therethrough, and a spring coiled about the hinge pintle for normally drawing the seat and plate together with its ends normally extending across the under side of the cut 5 out portions of the seat and adapted to engage upon the upper surfaces of the respective inturned ears allowing a limited up-

ward rotation of the clamping plate and adapted to be disengaged therefrom whereby the holder may be fully opened.

ALFRED G. WORMSER.
